UNITED STATES PATENT OFFICE.

HERMANN BUSCHER, OF LANGERFELD, NEAR BARMEN, GERMANY.

JACQUARD MECHANISM FOR LACE BOBBIN-MACHINES.

No. 853,396.

Specification of Letters Patent.

Patented May 14, 1907.

Application filed July 9, 1906. Serial No. 325,344.

To all whom it may concern:

Be it known that I, HERMANN BUSCHER, a citizen of the German Empire, residing at Langerfeld, near Barmen, in the Province of Westphalia and Kingdom of Prussia, Germany, have invented certain new and useful Improvements in and Relating to Jacquard Mechanism for Lace Bobbin-Machines; and I do hereby declare the following to be a full, 10 clear, and exact description of the invention, such as will enable others skilled in the art to which it appertains to make and use the same.

The subject-matter of the present invention is a new jacquard-mechanism for lace braiding-machines in which the bobbins can be temporarily stopped and in which consequently the devices for effecting this must be moved at different times and must also be 20 kept for a certain time in a determined position so that the jacquard-mechanism must work with temporary stoppages.

The jacquard-mechanism or its equivalent, otherwise ordinarily used for bobbin-machines are not applicable to these machines because in their case the lifting bar is moved continuously up and down, and it was moreover necessary always to arrange two such mechanisms on account of the necessary non-simultaneous actuation of the two stopping devices situated opposite one another. This however would in particular necessitate a very complicated formation and arrangement of the cords transmitting the action of the mechanism to the several stopping devices. Consequently special jacquard-mechanisms are used for the lace braiding-machines under consideration, in the case of which two systems of lifting-wires or lifters 30 each arranged in a row and each under the influence of a special lifting-blade are provided, said two lifting-blades being moved non-simultaneously, that is the one after the other, and working with temporary stoppages in the raised position. In the case of this jacquard-mechanism card-chains have hitherto been employed for regulating the motion of the lifters, said card-chains consisting of a suitably large number of wooden 40 slips jointed together and shaped cylindrically inside and outside, into which small rollers are inserted at the proper places when the lifters are to be kept out of reach of the lifting blades, said rollers being held upon wires. These chains are moved periodically 50 in such a way that for every movement of the lifting blades a new row of rollers is placed opposite the pushers which are arranged close together all in a row and which adjust the lifters. These card-chains of wood as 60 compared with the otherwise customary chains of separate cardboard strips possess however very considerable disadvantages. Their cost of production is very great and moreover it is very troublesome to arrange 65 the chains according to the particular design or pattern to be produced because each time it is necessary to insert the rollers properly as it is not feasible on account of expense to use the chains for only one design. The 70 most serious defect of these card-chains of wood is however that they are influenced by the weather existing at the time and changes in the weather produce alterations in the card-chain so that its uniformity and certainty of action are destroyed and consequently the various parts of the mechanism move irregularly and their irregular motion 75 is transmitted to the bobbins. In the case of the new jacquard-mechanism these defects have been completely avoided, a card-chain being employed which is formed of separate cardboard strips of the ordinary kind. In the case of this mechanism the two lifting-blades are by means of suitably shaped cam disks for example moved up and down independently of one another and the one after the other with the requisite stop in the end positions and the setting or adjustment of the two systems of lifters is effected 80 each time by means of the same card, the latter being provided with two rows of holes, of which the one co-operates with the needles of the one lifter-system and the other with the needles of the second system, the card-prism or cylinder being so moved by means of suitable cam disks or other equivalent means that it remains in its drawn-up position until even the lifting-blade rising last 85 has commenced its upward motion. 90

A new jacquard-mechanism according to the present invention is illustrated by way of example in the accompanying drawing, on which:

Figure 1 illustrates said jacquard-mechanism in sectional elevation, and Fig. 2 in plan, while Fig. 3 is an elevation of the mechanism as seen from the right of Fig. 1. Figs. 4 & 5 illustrate in elevation the cam-disks and adjacent mechanism for actuating the 95 100 105 110

Figure 1 illustrates said jacquard-mechanism in sectional elevation, and Fig. 2 in plan, while Fig. 3 is an elevation of the mechanism as seen from the right of Fig. 1. Figs. 4 & 5 illustrate in elevation the cam-disks and adjacent mechanism for actuating the 110

various parts of the mechanism and Fig. 6 represents one of the cards of the pattern-chain.

Referring to the drawing 1 are the lifting-wires or lifters of the one system and 2 those of the other system, said systems being arranged close to one another in two rows displaced or staggered with regard to one another in a manner which in other respects is the customary one. In their lowermost positions said systems rest upon the lifter-bottom 3. In correspondence with the two lifter-systems, two needle-systems 4, 5 are likewise provided, which are arranged the one above the other in two position, the needles 4 of the lifters 1 all being situated in the upper position and the needles 5 of the lifters 2 on the other hand being in the lower position. A separate lifting-blade 6 or 7 is provided for each lifter-system, said lifting-blades being secured to the one end of levers 8 or 9 respectively, which are revolubly mounted on a bar 10 provided in the upper part of the frame. The cam-disks 11 and 12 serve to operate the lifting-blades, said cam-disks being mounted on the shaft 13 which is driven in any suitable manner. The lower ends of the connecting-rods 14, 15 which straddle the shaft 13 engage in the grooves of the cam-disks 11, 12 respectively and their other ends engage with the backward extensions of the above-mentioned lever 8, 9 respectively. In order to enable the motion of the lifting-blades to be regulated, the connecting bolts between the connecting-rods 14, 15 and the levers 8, 9 respectively are arranged adjustably in the levers.

The card-cylinder 16 which possesses on each side two rows of holes the one above the other in correspondence with the two needle-systems 4, 5 is revolubly supported at its ends in bearings in slide-rods 17 which are mounted displaceably in a horizontal direction on the frame 18, so that by suitably moving these slide-rods the cylinder 16 can be pushed forward against the needle-board in order to set or adjust the lifters or can be pushed or backed off from the same. The slide-rods 17 are moved in this way by engaging in the grooves of cam-disks 19 which are driven from the shaft 13 by means of the toothed wheels 20, 21. The hook 22 in conjunction with the ratchet-wheel 23 effects the turning of the card-cylinder in the ordinary manner. Finally upon the latter is carried the card-chain 24 formed in the well-known manner of strips of card or paste-board of suitable breadth. As can be seen from Fig. 6 each card possesses two rows of holes of which the upper holes co-operate with the needles of the lifters 1 while the lower ones co-operate with the needles of the lifters 2. Consequently when the card-cylinder is pressed against the needles both

systems of lifters are set simultaneously by one and the same card in correspondence with the particular pattern to be produced.

The above-mentioned cam-disks 11, 12, and 19 are so shaped and are displaced or staggered with regard to one another in such a way that the card-cylinder is drawn up against the needle-board before the raising of the lifter-blade commences, and that after this the lifting-blade 7 is raised and then finally the lifting-blade 6 and that not until after the lifting-blade 6 has likewise commenced this movement the card-cylinder is moved away from the needle-board in order to set a new card in position for the following working cycle. The lifting blades which, as mentioned above, are actuated the one after the other remain moreover in their raised position as long as is called for by the arrangement of the bobbin-machine and its stopping-devices.

Having now explained the nature of my invention I declare that what I claim and desire to secure by Letters Patent is:

1. In jacquard mechanism, two lifter systems, in combination with two lifter-blades, operating respectively thereon in succession, with an interval of inaction, a card-chain and cylinder arranged to set both systems, means for actuating said blades, means for actuating said card chain and cylinder and means for regulating said cylinder, each card being provided with two sets of holes co-operating respectively with the needles of the said two systems, and the regulation of the cylinder keeping the card against the needle board till the lifting blade last to lift has begun this motion substantially as set forth.

2. In jacquard mechanism two lifter systems, in combination with two lifter blades, operating respectively thereon in succession, with an interval of inaction, a card chain and cylinder arranged to set both systems, a shaft carrying cam disks arranged for acting successively on said blades, rods interposed between said cam-disks and blades, cam-disks and co-operating mechanism for driving said cylinder and means for driving said shaft and all of said disks, each card being provided with two sets of holes co-operating respectively with the needles of the two lifter systems, one of the sets of needles being arranged lower than the other and said cylinder being regulated to keep the pattern card pressed up against the needle board until the lifting blade last rising has begun to lift substantially as set forth.

In testimony whereof, I have signed my name to this specification in the presence of two subscribing witnesses.

HERMANN BUSCHER.
